We claim the ornamental design for package and material for packaging, as shown and described.

DESCRIPTION

FIG. 1 is a top plan view of material for packaging according to our new design;

FIG. 2 is a right side view of a package, which is assembled from the material for packaging of FIG. 1;

FIG. 3 is a left side view thereof;

FIG. 4 is a front view thereof;

FIG. 5 is a rear view thereof;

FIG. 6 is a top view thereof; and,

FIG. 7 is a perspective view thereof.
